UNITED STATES PATENT OFFICE.

WILLIAM WOELFEL, OF PEABODY, MASSACHUSETTS.

GUARD FOR POWER PRESSES OR THE LIKE.

1,405,957.

Specification of Letters Patent. Patented Feb. 7, 1922.

Application filed March 9, 1920. Serial No. 364,592.

To all whom it may concern:

Be it known that I, WILLIAM WOELFEL, a citizen of Austria, and resident of Peabody, in the county of Essex and State of Massachusetts, have invented new and useful Improvements in Guards for Power Presses or the like, of which the following is a specification.

My invention relates to a guard for power presses or the like, and more particularly to a guard adapted to be used in connection with a safety stop for such machines.

In the use of heavy power embossing or punch presses or the like, serious injury to the hands of an operator often results from delay in removing the hands from between the jaws of the press. In such presses it is usually necessary for the hands to be used in placing the work in the press and there is a tendency to attempt to speed the work up by having the press close as the hands are withdrawn, with consequent danger to the operator. Furthermore the operator will at times attempt to straighten a piece of work or remove foreign matter by reinserting his hand after the press has started to close. It has been found in practice that any safety device which depends upon any voluntary act of the operator for the safety afforded is of doubtful utility, if not useless.

One of the most dangerous types of press is that at which two persons work on opposite sides but only one operates the press. An attempt has been made to afford safety in certain types of these large presses having two workers operating thereon by placing a foot board in front of the worker who does not operate the press, pressure on the foot-board serving to prevent the operation of the press. It has been found in practice, however, that the worker will neglect to place his foot upon the board and, being almost entirely hidden from the operator by the press, is in constant danger of having his hands injured.

My improved guard is of particular utility in connection with machines having so called safety footboards of the character described.

It is an object of my invention to provide an improved means whereby workers upon power presses or the like machines will positively protect themselves against injury. It is an object to so equip such machines that the worker can not operate the machine without operating the safety device. It is a

further object to provide means of the character described which are simple and efficient in operation and formed of but few parts, all of which are capable of inexpensive manufacture. Other and further objects will appear as the disclosure proceeds.

In its broadest aspect my invention comprises the provision of means in connection with the usual operating or safety control levers of a machine whereby the machine can not be controlled without the safety devices coming into operation. In the specific embodiment which is herein fully described and shown by way of example, my invention comprises a lever in connection with the safety footboard of a power press and a guard associated with such lever whereby work can not be placed or adjusted in the press unless the lever is depressed to raise the guard, the depression of the lever further serving to depress the safety footboard and prevent operation of the press while the guard is raised.

I have illustrated one preferred form of my device in the accompanying drawings in which,

Figure 1 is a face view of a power press showing my guard mounted thereon,

Figure 2 is a view of Fig. 1 as seen from the left side.

Fig. 3 is a fragmentary side elevation, illustrating details of the connection between the operating lever and the safety device; and

Fig. 4 is a fragmentary detail front elevation to large scale, showing a guiding bracket for one of the movable parts of the mechanism.

In order to properly show the application of my device I have found it necessary to illustrate a power press in a diagrammatic manner. This press forms in itself no part of my invention and as shown comprises a base member 3, standards 4, cap member 5, upper fixed abutment 6, lower movable abutment 7, hand lever 8 and foot pedal 9 connected by link 10 to the safety footboard 11 whose other end is hung from the base member by the stirrup 12.

It will be understood that in the use of the type of press indicated in the drawings, two workers stand one on either side of the press as seen in Fig. 2, the one on the right side normally feeding the work into the press and the one on the left assisting in adjusting

the work and also operating the parts either by pulling forwardly on the member 8 or depressing the pedal 9, the shaft 50 upon which said lever and pedal are fixed serving to control a clutch whereby the driving mechanism of any usual form (not shown) is actuated to cause the abutments or jaws of the press to close together. The safety foot board 11 has been provided for the safety of the worker other than the operator, the worker being expected to place his foot thereon while he is working between the jaws of the press, his weight acting through the link 10 and serving to prevent movement of the lever 8 or pedal 9, and consequently to prevent the operation of the press.

There is nothing, however, to require the worker to place his foot upon the safety board except his own desire to protect himself and it has been found in practice that workers commonly neglect to do so with consequent danger and occasional injury to themselves.

My invention makes it necessary for the worker to place his foot upon the safety board in order to work with the machine. As shown in the drawings my device comprises a horizontal shaft 14 which is supported by brackets 15 which are fast to a fixed portion of the press. Rigidly connected to this shaft 14 is the guard screen 16, the weight arm 17 carrying the weight 18 and the actuating arm 19. The weight arm 17 normally rests in a fork comprising spaced members 20^a, 20^b in the upper end of the bracket 20 which is attached to any fixed portion of the press, being here shown attached to the abutment 6. The actuating arm 19 is connected by the bar or cable 21 and link 22 to the foot actuating lever 23 which is hinged at 24 to the foot board 11. A spring 25 normally maintains the foot lever in the position shown in Fig. 1.

As clearly shown in the drawings the screen 16 when down, covers the opening between the jaws of the press and prevents an operator placing his hands therebetween. This screen may be raised by placing the foot upon the foot lever 23, which pulls down upon the bar or cable 21 and consequently upon the actuating arm 19 and this turns the shaft 14, the screen rotating upward out of the way. This pressure upon the foot lever 23 is directly transmitted to the safety foot board 11 and thus through the link 10 and intermediate connections restrains the lever 8 against forward movement such as is necessary to start the press.

When the foot is removed from the foot lever, this member is raised by the spring 25, releasing the pull upon the actuating arm 19 and the screen falls to the safety position, partly due to its own weight and partly due to the weight 18 upon the weight arm 17. As shown this weight may be ad-

justed upon the arm to give it more or less leverage and thereby to vary somewhat the speed of drop of the screen and also the force with which the screen will strike the hands of the operator if they have not been removed before the screen drops.

While I have shown my improved guard in connection with one particular form of press it is obvious that its operation is independent of that of the apparatus with which it is associated and that it may be used in connection with other types of apparatus where a guard is necessary or desirable.

When used as shown it is practically impossible for the worker to place work upon the machine unless the safety foot board is depressed and pressure on that board can not be released to permit operation of the machine without dropping the guard which requires removal of the hands of the worker from dangerous proximity to the press.

I claim:

1. A double power press having clutch actuating means at one side thereof, and a safety device at the other side, a guard for the press and means for raising said guard out of the protecting position, said means being so associated with the safety device of the press as to require operation of that device in operating the means for raising the guard.

2. A double power press having a clutch operating device at one side thereof, and a foot safety board at the other side, a guard for the press and means for raising said guard out of the protecting position, said means being so associated with the foot safety board of the press as to require operation thereof in operating the means for raising the guard.

3. A power press comprising a movable safety device, a guard adapted normally to cover the space between the jaws of the press and a manually actuatable lever for raising said guard out of its normal position, said lever being supported by the safety device of the press whereby to necessitate operation of that device in operating the lever for raising the guard.

4. In combination with a power press and with the foot safety board thereof, a guard normally adapted to prevent a worker from placing his hands in dangerous proximity to the machine, and a foot lever associated with said guard and adapted to so move the guard as to permit access to the machine when said foot lever is depressed, the foot lever being so associated with the foot safety board as to actuate said board when the said foot lever is depressed.

5. In combination with a power press having a foot safety board associated therewith, the board when actuated being adapted to prevent operation of the press, a guard member normally in guard position, and an

- actuating lever for said guard mounted on said foot board adapted when depressed to raise the guard out of guard position.
6. In combination with a power press having a foot safety board associated therewith, the board when actuated being adapted to prevent operation of the press, a guard member normally in guard position, an actuating lever for said guard mounted on said foot board adapted when depressed to raise the guard out of guard position, and so associated with the foot board that pressure on said actuating lever actuates said foot board.
- 15 7. In combination with a power press having a foot safety board associated therewith, the board when actuated being adapted to prevent operation of the press, a guard member normally in guard position, an actuating lever for said guard mounted on said foot board and adapted when depressed to raise the guard out of guard position, the guard being adapted to be returned to the guard position by gravity upon release of pressure upon said actuating lever.
- 25 8. In combination with a power press having a foot safety board associated therewith, the board when actuated being adapted to prevent operation of the press, a guard member normally in guard position, an actuating lever for said guard mounted on said foot board adapted when depressed to raise the guard out of guard position, and so associated with the foot board that pressure on said actuating lever actuates said foot board, the guard being adapted to be returned to the guard position by gravity upon release of pressure upon said actuating lever.
- 30 9. In combination with a power press having a foot safety board associated therewith,
- the board when actuated being adapted to prevent operation of the press, a guard member normally in guard position, an actuating lever for said guard mounted on said foot board adapted when depressed to raise the guard out of guard position, and so associated with the foot board that pressure on said actuating lever actuates said foot board adapted to be returned to the guard position by gravity upon release of pressure upon said actuating lever.
- 35 10. A double power press, having a clutch operating device at one side and a safety device at the opposite side, comprising in combination a guard member, a shaft for said member, and an actuating arm extending from said shaft, an actuating lever linked to the actuating arm and adapted when depressed to pull down the arm and thereby move the guard out of guard position, and simultaneously to move said safety device to safety position.
- 40 11. A guard for use with power presses comprising a guard member normally held in the guard position by gravity, a shaft for said member, a weight arm and an actuating arm extending from said shaft, the weight arm carrying an adjustable weight adapted to assist in returning the guard to normal position, an actuating lever linked to the actuating arm and adapted when depressed to pull down the arm and thereby move the guard out of guard position, and a spring normally maintaining the actuating lever in raised position.

Signed by me at Peabody, Massachusetts,
this fifth day of March, 1920.

WILLIAM WOELFEL.
